CLAIM

The ornamental design for a baby inflatable seat, as shown and described.

DESCRIPTION

FIG. 1 is a front perspective view of a baby inflatable seat of the present disclosure;

FIG. 2 is a side perspective view thereof;

FIG. 3 is a top perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines depict portions of the baby inflatable seat that form no part of the claimed design.
